(57)

CLAIM

The ornamental design for a printing kiosk, as shown and described.

DESCRIPTION

FIG. 1 is a right front perspective view of a printing kiosk showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a right rear perspective view thereof.

(Continued)

The broken lines in the figures and the areas within the broken lines show portions of the printing kiosk that form no part of the claimed design.

1 Claim, 8 Drawing Sheets
